APPARATUS FOR PRODUCING HIGH DENSITY PLYWOOD TUBING

John A. Miller, De Kalb, Ill., assignor to The Rudolph Wurlitzer Company, Chicago, Ill., a corporation

Application June 6, 1942, Serial No. 446,100

6 Claims. (Cl. 144—268)

This invention relates to an apparatus for producing high density plywood tubing through impregnation by suitable filler and compression through the application of high pressure while in a heated condition.

High density plywood tubing has great strength, is impervious to the elements and has insulating qualities which adapt it to many structural uses. It may be of varying cross section, but is usually cylindrical, and also usually of uniform diameter. Furthermore, the tubing may be formed through the spiral winding of wood veneer including the cross winding thereof where desired, or may be formed by lap winding, or any combination of straight lap winding and cross or direct spiral winding. The lapping or winding of the veneer to form the plywood tubing is accompanied by the application of the thermo-setting glue as a bonding material therefor. The wrappings of veneer may be entirely impregnated, or some of the veneer or laminae may be impregnated while some is unimpregnated. However, the density of the tubing is varied or controlled by the extent of the impregnation thereof so that it may be said that the more extensive the laminae is impregnated, the higher will be its density—all else being equal. Preferably the impregnation may comprise the application of a thermo-setting resin and its penetration of the wood fibres through the application of heat and pressure. Thus, through suitable application and processing of the veneer with a thermo-setting resin, pressure under heat may be applied, such as to actually reduce the normal thickness of the plywood by fifty percent, with a corresponding increase in density. This may be accomplished by reason of the soft, compressible and flowing character of the fibres so treated with the impregnating material and the application of heat.

A feature of this invention resides in the apparatus for applying external pressure in the forming of plywood tubing for effecting the desired compression thereof.

Another feature of the invention resides in such application of external pressure while the tubing is subjected to a highly heated condition.

Another feature of the invention resides in the application of pressure to the surface of the tubing simultaneously with the application of heat thereto and while in a state of impregnation by a suitable material such as a thermo-setting resin.

The full nature of the invention will be under-

stood from the accompanying drawings and the following description and claims:

Fig. 1 is a perspective view of the apparatus for applying external pressure about the tube. Fig. 2 is a layout of the pressure applying wrapping member. Fig. 3 is a perspective view of the underside of the tubing showing the interlacing of the strips of wrapping material, with sections thereof broken away.

- 10 In the drawings there is shown for purpose of illustration, a cylindrical mandrel 10 for receiving and providing the support and inner surface form for the plywood tubing to be compressed to high density. This mandrel may be of varying shapes and cross section or tapered, depending upon the form and shape of tubing to be produced. It is adapted to receive the plywood tubing after being formed and treated with the bonding and impregnating material. The tubing having been first formed, is preferably cut into sections of the desired length and mounted endwise of the mandrel 10, and within the loosened wrappings of a sheet metal protective shell 11 and the wrapping member. The protective shell 11 is preferably formed of thin polished spring metal and is normally in loose cylindrical formation within which the tubing is conveniently inserted and covered so that the edges of the shell overlap as illustrated in Fig. 3.
- 15 20 25 30 35 40 45 The wrapping member, as illustrated in Fig. 2, is formed of thin spring steel having a body portion 12 with laterally-extending strips 13 extending from opposite sides thereof and in staggered relation, each group of strips being of the same width as the spacing therebetween. The wrapping member is of such dimensions that for a given size tubing it will extend over the full length thereof and the body portion will wrap thereabout substantially one lap, whereas the strips 13 will interlace with respect to each other and pass around the body portion and tubing with one lap before extending in opposite directions.

The mandrel 10 is supported upon or in relation to, in any suitable manner, a base plate 14 and is arranged to provide suitable heat for the tubing compressed thereon through any suitable heating means, such as the steam pipes 15, or said tubing may be connected as an electrode with a high frequency generator for subjecting the tubing to a high frequency electrical field for generating heat therethrough.

The wrapping member is anchored at one end to the base plate. Thus, there may be secured at one end of the base plate a lower clamping bar

16 and an upper clamping bar 17 between which the ends 18 of the strips 13 may be clamped and secured by suitable screws 19. The opposite ends of the wrapping member are anchored to a tension bar slidably supported upon the base plate and comprising the lower clamping bar 20 and upper clamping bar 21 to which the ends 22 of strips 13 are secured by the screws 23. Said tension bar is provided with internally threaded sleeves 24 into each of which a threaded tension rod 25 extends. Each of said rods also extends through suitable sleeves 26 mounted on a crank block 27. The operative ends in each of said tension rods are provided with a crank handle 28. The base plate may be calibrated along opposite edges thereof for the purpose of indicating the compression to which the plywood tubing 30 has been subjected and to control the extent of compression at opposite ends thereof.

The wrapped veneer or plywood tubing may be subjected to such pressure by the wrappings and drawing apart of the strips of the wrapping member as to effect a compression thereof controlled by the positioning of the tension bar, and wherein the fibres have been rendered soft and pliable through the impregnation thereof by the plastic under such heat as to cause a certain amount of flow.

The invention claimed is:

1. Apparatus for producing high density plywood tubing comprising a mandrel over which preformed plywood tubing is mounted, means associated with said mandrel for heating the tubing thereon, a sheet metal wrapping surrounding the tubing and having oppositely extending strips in spaced and staggered relation adapted to interlace to extend in opposite directions, a fixed clamping member to which the strips on one side of the tubing are secured, a movable clamping member secured to the oppositely-extending strips, and means for drawing said movable clamping member to apply sufficient tension to said strips to compress the plywood to a fraction of its normal thickness.

2. Apparatus for producing high density plywood tubing comprising a mandrel over which preformed plywood tubing is mounted, means associated with said mandrel for heating the tubing thereon, a sheet metal wrapping member having a body portion overlying and extending about the tubing, said body portion being formed with a series of integral and laterally-extending strips spaced from each other and formed in staggered relation on opposite sides of said body portion, means for anchoring the strips on one side of said body portion, and means for exerting tension on the oppositely-extending strips for drawing the body portion taut to apply pressure about the tubing to compress the plywood thereof to a fraction of its normal thickness.

3. Apparatus for producing high density plywood tubing comprising a mandrel over which preformed plywood tubing is mounted, means

associated with said mandrel for heating the tubing thereon, a sheet metal shell surrounding said tubing with its edges overlapping, a wrapping member surrounding said shell and having a body portion and oppositely extending interlaced strips, a base plate, a clamp on said base plate for anchoring the strips extending from one side of said body portion, a tension bar secured to the strips extending from the opposite side of said body portion, and means on said base plate for exerting force on said tension bar sufficient to draw said wrapping member taut about the tubing for exerting sufficient pressure thereabout to compress the plywood to a fraction of its normal thickness.

4. Apparatus for producing high density plywood tubing comprising a mandrel over which preformed plywood tubing is mounted, means associated with said mandrel for heating the tubing thereon, a sheet metal shell surrounding said tubing with its edges overlapping, a wrapping member surrounding said shell and having a body portion and oppositely extending interlaced strips, a base plate, a clamp on said base plate for anchoring the strips extending from one side of said body portion, a tension bar secured to the strips extending from the opposite side of said body portion, means on said base plate for exerting force on said tension bar sufficient to draw said wrapping member taut about the tubing for exerting sufficient pressure thereabout to compress the plywood to a fraction of its normal thickness, and tension registering means associated with said tension bar for indicating the pressure applied at opposite ends of the tubing.

5. Apparatus for producing high density plywood tubing, comprising a mandrel over which preformed plywood tubing is mounted, a sheet metal wrapping surrounding the tubing and having oppositely extending strips arranged in spaced and staggered relation adapted to interlace for permitting them to extend in opposite directions from said wrapping, and means connected with said strips operable to draw them in their respective opposite directions and thereby apply sufficient tension to said strips and wrapping to compress the plywood to a fraction of its normal thickness.

6. Apparatus for producing high density plywood tubing, comprising a mandrel over which preformed plywood tubing is mounted, a sheet metal shell surrounding said tubing, a wrapping member surrounding said shell and having a body portion with outwardly extending interlaced strips extending in opposite directions, and means connected with said oppositely extending strips respectively operable to place them under tension in opposite directions for drawing the body portion of said wrapping member taut about said shell and tubing to thereby exert sufficient pressure thereon to compress the plywood to a fraction of its normal thickness.
